(57) **CLAIM**

The ornamental design for a cuff with connector as shown and described.

DESCRIPTION

FIG. 1 is a top-front-left perspective view of a cuff with connector according to the claimed design, with a wireless sensor shown in environment.

FIG. 2 is a top view of the cuff with connector of FIG. 1 with the wireless sensor shown in environment.

FIG. 3 is a bottom view of the cuff with connector of FIG. 1.

FIG. 4 is a left side view of the cuff with connector of FIG. 1 with the wireless sensor shown in environment.

FIG. 5 is a right side view of the cuff with connector of FIG. 1 with the wireless sensor shown in environment.

FIG. 6 is a rear view of the cuff with connector of FIG. 1 with the wireless sensor shown in environment; and, FIG. 7 is a front view of the cuff with connector of FIG. 1 with the wireless sensor shown in environment.

The dash-dash broken lines and the oblique broken line hatch shading in the drawings illustrate portions of the cuff with connector and environmental matter that form no part of the claimed design.

FIGS. 1-2 and 4-7 show a wireless sensor coupled to the cuff with connector. The wireless sensor is environmental matter and forms no part of the claimed design.

1 Claim, 7 Drawing Sheets
